FIG. 1

FIG. 2

FIG. 1 is a perspective view of a tire showing my novel design, it being understood that the tread pattern is repeated throughout the circumference of the tire shown schematically in solid lines, the opposite side being substantially the same as that shown, and

FIG. 2 is an enlarged fragmentary developed plan view of the tire shown in FIG. 1.

I claim:

The ornamental design for a tire, substantially as shown and described.
